UNITED STATES PATENT OFFICE

NORRIS E. GOODRICH AND JOSEPH CONNOR, OF BATTLE CREEK, MICHIGAN, ASSIGNEES
TO SANITARIUM EQUIPMENT COMPANY, OF BATTLE CREEK, MICHIGAN

DESIGN FOR A THERAPEUTIC LAMP

Application filed April 10, 1931. Serial No. 39,431. Term of patent 7 years.

To all whom it may concern:

Be it known that we, NORRIS E. GOODRICH and JOSEPH CONNOR, citizens of the United States, residing at Battle Creek, in the county of Calhoun and State of Michigan, have invented a new, original, and ornamental Design for a Therapeutic Lamp, of which the following is a specification, reference being had to the accompanying drawing, forming part thereof.

The figure is a perspective view of a therapeutic lamp, showing our new design.

We claim:

The ornamental design for a therapeutic lamp, as shown.

NORRIS E. GOODRICH.
JOSEPH CONNOR.
